HYGIENIC TOOTHPICK DISPENSER

Raphaël Lépine, Hawkesbury, Ontario, Canada

Application February 12, 1947, Serial No. 728,065

4 Claims. (Cl. 312—75)

1

The present invention relates to improvements in an hygienic toothpick dispenser and appertains particularly to a manually operated dispensing machine for presenting a single article at a time in convenient position to be withdrawn.

An object of the invention is to provide a sanitary dispenser for toothpicks or the like that holds a supply of the articles, completely enclosed and shielded from dust, germs, etc., and untouched by other persons may be passed out singly and as required in fresh, new condition.

A further object of the invention is to provide a dispenser for thin elongated articles that feeds one article at a time, ejecting it horizontally and delivering it endwise.

A further object of the invention is to provide a dispenser for elongated articles with a horizontal and endwise delivery, wherein the supply of articles stored in the dispenser is kept level, orderly and feeding to the ejecting mechanism by a novel vibrator mechanism associated with the ejector.

A further object of the invention is the provision of a dispenser for toothpicks, and like articles, that is characterized by structural simplicity, may usefully display advertising matter on its face and, being capable of manufacture at reasonable cost, is thereby rendered commercially desirable.

To the accomplishment of these and related objects as shall become apparent as the description proceeds, the invention resides in the construction, combination and arrangement of parts as shall be hereinafter more fully described, illustrated in the accompanying drawings, and pointed out in the claims hereunto appended.

The invention will be best understood and can be more clearly described when reference is had to the drawings forming a part of this disclosure wherein like characters indicate like parts throughout the several views.

In the drawings:

Figure 1 is a front elevation of an hygienic toothpick dispenser embodying my invention;

Figure 2 is a vertical, transverse section therethrough, as taken on line 2—2 of Figure 1;

Figure 3 is an enlarged perspective elevation of the novel ejecting mechanism; and

Figure 4 is a fragmentary perspective elevation of the front of the hopper.

While I shall describe my instant invention as a toothpick dispenser, it must be understood that wherever reference is made to a toothpick or the term toothpick is employed it designates gen-

2

erally any thin elongated article such as a match, cigarette, sipping straw, pin or the like.

In the illustrated embodiment of the invention the casing, cabinet or jacket is in the form of a hollow rectangular box 5, almost square from the front and about twice as high as it is thick. The sides 6, bottom 7 and back 8 are opaque but the front 9 and top 10 are of transparent plastic—this enables the display of covered advertising matter (not shown) behind the front 9 and top 10 and the inclusion of unobstructed areas of either to afford a view of the supply of toothpicks within the container to ascertain when replenishment is needed. The top 10 is removably held by rotatably releasable fasteners 11 that can be turned crosswise with respect to an accommodating narrow slot in the cover.

A hopper 12 occupies the upper half of the jacket 5, and the two companion sloping wings 20 thereof, disposed one on either side of the vertical median of the box, extend from the front 9 to the back 8, except that a spacing or filler plate 13 is shown as applied to the upper, inside part of the back. Across the bottom of the hopper, 25 there is a passageway 14 as the converging wings fail to meet, being bevelled to drop vertically in spaced relation. Under the front of the hopper 12 and closing this passageway 14 for a short distance is a prop 15 whose upper end is tenoned 30 to rise between the hopper wings and is cut with a V notch 16 on its top surface.

The ejecting mechanism for dispensing one toothpick at a time from a supply thereof stacked in the hopper 12 and feeding by gravity to the 35 passageway 14 at its bottom consists of a horizontal shaft 17 rotatably journaled at opposite ends in the sides 6 of the jacket. A disk-like member 18, of a thickness to move nicely between the spaced bevelled bottoms of the hopper wings 40 and of a diameter to rise approximately to the level of the prop's notched top 16 is mounted on the shaft 17 and through its uppermost arc has a V-groove 19 cut in its periphery. To the rear, and somewhere between 45° and 90° from the vertical, this groove 19 ends abruptly in a radial projection 20. Rubber has been found a very suitable material from which to construct this ejector disk. The rubber disk is applied laterally to the relatively heavy-solid shaker or vibrating 45 block 21 that underlies one of the hopper wings. It rounds away at the back but serves as a "stop" to limit the rearward rotation of the disk 18 when the shoulder 22 on its forward side comes in contact with the underside of the hopper.

Secured to the block 21 and extending to the

side is a spool-like spacer 23 on the outside of whose enlarged end is a plate 24 with a perforated radial lug 25 through which the offset lower end 26 of the push rod 27 extends. This rod rises through a guide eyelet 28 in the side wall 6 and passing through a slot in the top 10 terminates above the latter in a horizontal spiral configuration 29 that serves as a finger plate. The rod 27 and radial lug 25 may be so arranged that the depressing of the rod 27 can rotate the shaft 17 through anything up to about 165° but I prefer to relate the angular setting of this lug with respect to the stop 22 so that a rotation of the shaft 17 through an angle of only approximately 45° to 60° is permitted. A resetting retractile coil spring 30 is stretched between the forward upper side of the block 21 and the back of the casing 8 or rear spacer plate 13 near the top and just to the side of the hopper.

Rising from a level just below the bottom of the V-shaped notch in the prop tenon 16 or substantially aligned with the said notched tenon top and the grooved periphery of the ejector disk 18, is a perforation 31 in the casing front 9 through which the toothpicks, fresh, clean and untouched-by-human-hands, are fed out one at a time on operation of the manually operable rod 27.

So it will be seen that the pressing down of the rod 27 rotates the ejector disk 18, causing the stepped projection 20 thereof to ride over the top and push outwards any thin elongated article that was nested in its groove 19 and riding in the co-level notch 16 of the prop 15. On release of the rod 27 it rises again under the influence of the spring 30 that snaps the whole ejector mechanism back to initial setting where it stops as the shoulder 22 of the block 21 strikes sharply against the bottom of the hopper 12, shaking the same by the impact. This shaking or vibrating of the hopper 12 by the impact of the block 21 on every operation of the rod 27 is important in keeping the toothpicks in orderly arrangement in the hopper with the lowermost toothpick settling evenly in the notch in the top of the front prop and the groove in the disk and aligned with the outlet opening 31 in the front of the cabinet ready to be ejected by the radial projection 29. For this purpose I prefer the hopper assembly including the back spacer to which the hopper wings attach and the front prop to be loosely mounted with respect to the rest of the device.

From the foregoing description taken in connection with the accompanying drawings, it will be manifest that an hygienic toothpick dispenser is provided that will fulfill all the necessary requirements of such a device but as many changes could be made in the above description and many apparently widely different embodiments of the invention may be constructed within the scope of the appended claims without departing from the spirit or scope thereof, it is intended that all matters contained in the said accompanying specification and drawings shall be interpreted as illustrative and not in a limitative or restrictive sense.

Having thus described my invention, what I claim as new and desire to secure by Letters Patent is:

1. A dispenser comprising a casing having a removable top, a hopper in said casing formed of a pair of sloping wings narrowly spaced at their lower ends, a prop under the forward side of said hopper having a spacing tenon rising between the wings thereof, a manually operated

spring retracted ejector disk rising between the spaced lower ends of said hopper wings and substantially level with the tenon of said prop, a stop on the side of said disk in normal engagement with the underside of one of said hopper wings, and an opening in said casing substantially aligned with the top of said ejector disk and the tenon of said prop.

2. A dispenser comprising a casing having a removable top, a hopper in the upper part of said casing and replenishable through said top formed of a pair of sloping wings narrowly spaced at their lower ends, a prop under the forward side of said hopper having a spacing tenon rising between the wings thereof, a manually operated, spring retracted ejector disk rising between the spaced lower ends of said hopper wings and substantially level with the tenon of said prop, substantially aligned V-shaped grooves in the top of said tenon and in the periphery of said disk respectively, a stop on the side of said disk in normal engagement with the underside of one of said hopper wings, and an opening in said casing substantially aligned with the grooved top of said ejector disk and the tenon of said prop.

3. An hygienic dispenser for endwise delivery of toothpicks and like thin elongated objects comprising a casing having an outlet perforation in the front thereof; a loosely mounted hopper assembly therein consisting of a pair of sloping hopper wings one on either side of the casing's centre, running from front to back and converging toward the bottom, a spacing plate across the back of said wings and a prop under the forward end of said wings; a rotatable ejecting disk in the bottom of said hopper and substantially level with the outlet perforation in the front of said casing; a hopper assembly shaking stop affixed laterally to said ejecting disk; a retractile spring normally holding said stop in engagement with the bottom of said hopper; and manually operable, disk actuating means acting against said spring.

4. An endwise delivering dispenser for thin elongated articles comprising a casing having a base, front and back and side walls and a removable top, said front having an outlet perforation about its centre; a hopper in the upper part of said casing, accessible through the open top thereof, consisting of a pair of sloping wings extending from front to back and converging toward their lower ends; a rotatable horizontal shaft in the lower part of said casing and underlying said hopper with its ends journalled in opposite side walls of said casing, a lug extending radially from said shaft; a vertically slidably, manually operable rod pivoted to said lug and rising through the top of said casing; a stop on said shaft; a retractile spring associated with said shaft against which said rod acts; and an ejector on said shaft with its top reaching into the bottom of said hopper and level with the outlet perforation in the front of said casing.
